(57) **CLAIM**

The ornamental design for a stepladder rail handle, as shown and described.

DESCRIPTION

FIG. 1 is a perspective view of a stepladder rail handle showing our design;

FIG. 2 is a front elevation view thereof;

FIG. 3 is a rear elevation view thereof;

FIG. 4 is a bottom plan view thereof;

FIG. 5 is a top plan view thereof;

FIG. 6 is a left elevation view thereof;

FIG. 7 is a right elevation view thereof; and,

FIG. 8 is perspective view thereof, with the stepladder rail handle in a condition of use installed onto a stepladder shown in broken lines.

The broken lines on the stepladder rail handle show portions that form no part of the claimed design. The broken lines showing a stepladder in FIG. 8 illustrate environmental structure associated with the design in a condition of use and also form no part of the claimed design.
